CONDENSER FOR REFRIGERATING SYSTEMS

Frederick R. Erbach, Detroit, Mich., assignor to Kelvinator Corporation, Detroit, Mich., a corporation of Michigan

Application December 19, 1927, Serial No. 241,073

4 Claims. (Cl. 62—115)

My invention relates to the science of mechanical refrigeration and it has particular relation to a novel type and arrangement of condensing unit adapted to be employed as a portion of mechanical refrigerating mechanism.

In the mechanical refrigerating art it is customary to employ, in a closed refrigerant medium circuit, a compressor, a condenser and an evaporator, or cooling unit. The refrigerant, in its gaseous state is compressed by the compressor, cooled and condensed by the condenser and subsequently gasified in the evaporator.

Heretofore, it has been customary, to employ condensers of the so-called "bird-cage" type, which consists of a large rectangular coil of tubing, so disposed as to surround the compressor, which is cooled by a current of air caused by a fan, which is driven by the same source of power as is the compressor. The chief objection to this type of condenser is that it is bulky, and, because of its low efficiency as a heat transferring device, the employment of a large amount of tubing is necessary, which renders it expensive to construct.

By my invention I have eliminated these objections by providing a novel type of condenser which has a high heat transfer capacity, which is simple and inexpensive to manufacture, and which lends itself not only to a compact arrangement of the component parts thereof, but also to compact arrangement with the other units of the refrigerating mechanism.

One object of my invention consists in providing a novel type of condenser.

Another object of my invention is to provide a novel arrangement of the condenser and the compressor driving motor, and which is particularly adapted for use in connection with refrigerating mechanisms.

For a better understanding of my invention, reference may now be had to the accompanying drawings of which

Fig. 1 is a side elevational view of a motor compressor unit provided with a condenser constructed in accordance with my invention;

Fig. 2 is a plan view, partially in section, of the condenser illustrated in Fig. 1, and

Fig. 3 is a side elevational view of the structure illustrated in Fig. 1.

In the drawings I have illustrated a compressor provided with a superstructure or dome 11 and adapted to be driven by an electric motor 12 through a speed reducing worm gear mechanism contained within the gear housing 13, mounted upon a supporting mechanism 14. Mounted on

top of the motor 12 is a guard or fan housing 15 which serves as a support for a condenser 16. A fan 17, mounted upon the shaft of the motor 12, draws cooling air through openings 18 in the fan housing 15 and forces it through the condenser 16.

As best illustrated in Figs. 2 and 3, the condenser 16 consists of an outer shell or casing 20, the lower edge 21 of which is substantially horizontal, and is secured to the top of the fan housing 15 by means of bolts 22. The upper edge 23 of the casing 20 is similarly inclined along two oppositely disposed sides. Disposed within the shell 20 is a radiator core 24, consisting of a plurality of tubes 25 arranged so as to form three rows of tubes each parallel with the inclined portion of the edge 23, and a plurality of spaced heat radiating fins 26, either integral with portions of the tubes 25 or rigidly secured thereto, are disposed at right angles to the tubes 25. By means of connecting member 27, of substantially U-shape, the tubes of each row are connected in series, constituting three parallel paths of constant inclination for the refrigerant to follow.

The upper ends of each of the rows of tubes 25 are connected to a header or fitting 28, and, in like manner the lower ends of the rows of tubes are connected to a similar header 29. The header 28 is connected, by means of a tube 30 of relatively large cross-sectional area, to the top of the dome or superstructure 11 mounted on the compressor. The lower header 29 is connected by means of a tube 31, of relatively smaller cross-sectional area, to the lowermost portion of the dome 11. The refrigerant, in the form of gas, is discharged under pressure into the dome 11 by the compressor. The tube 30 carries the gas to the header 28, which distributes it into three parallel inclined paths through the tubes 25. As the gas is cooled by contact with the tubes 25, it condenses or liquefies, and in the form of liquid drains through the remainder of the tubes 25 into the header 29, thence through the tube 31 and back into the dome 11. From the dome 11 the liquid refrigerant passes into the evaporator (not shown) of the system where it is reconverted into gas and is drawn therefrom by the compressor to be again compressed.

It will be observed that, by the employment in the condenser, of tubes which are disposed at a constant inclination throughout their entire length, the formation of liquid pools or traps in any portion of the tubes is prevented, which interfere with the proper movement of gaseous refrigerant therethrough, and lower the efficiency of the condenser. Also, it is apparent that, by

use of the headers associated with the tubes of the condenser I am enabled to secure a plurality of parallel paths for the travel of the refrigerant through the condenser, thus increasing its capacity. By means of the fan housing 15, I am enabled to mount the condenser 16 directly over the motor 12 which has mounted on the shaft thereof the fan 17, thus providing a particularly simple and compact arrangement of the condenser and motor compressor unit.

Although I have illustrated but one form of my invention and have described in detail but a single application thereof, it will be apparent to those skilled in the art that it is not so limited but that various modifications and changes may be made therein without departing from the spirit of my invention or from the scope of the appended claims.

What I claim is:

- 20 1. In combination, a compressor, a vertically disposed motor operatively connected thereto, a condenser connected to said compressor and mounted over said motor, said condenser having a bank of tubes disposed in uniform relation to a plane inclined with respect to the horizontal and having an inlet connection adjacent its upper extremity and an outlet connection adjacent its lower extremity, and a fan mounted on said motor adapted to move cooling fluid through said condenser in an oblique relation to said bank of tubes.

2. In combination, a motor having a vertically disposed shaft projecting therefrom, a fan mounted on the shaft, a condenser having a bank of tubes disposed in a plane inclined with respect to the horizontal and positioned to receive a blast of air discharged from said motor fan, means for connecting the upper end of the condenser to the high side of a refrigerant compressor, and means for discharging condensed refrigerant liquid from the lower extremity of the condenser.

3. In combination, a refrigerant compressor, a motor having a vertically disposed shaft for driving said compressor, a fan mounted on the shaft, and a condenser for receiving a blast of air from said fan, said condenser having a plurality of parallel banks of tubes disposed in planes intersected by the motor shaft at oblique angles.

4. In combination, a motor having a shaft projecting therefrom, a fan mounted on the shaft, a condenser having a bank of tubes disposed in a plane inclined with respect to the horizontal and positioned directly in front of said fan to receive substantially the entire blast of air discharged by said motor fan, means for connecting the upper end of the condenser to the high side of a refrigerant compressor, and means for discharging condensed refrigerant liquid from the lower extremity of the condenser.
